(57) CLAIM

The ornamental design for a football hooded bath garment, as shown and described.

DESCRIPTION

FIG. 1 is a front perspective view of the football hooded bath garment;

FIG. 2 is a rear perspective view of the football hooded bath garment of FIG. 1;

FIG. 3 is a front plan view of the football hooded bath garment of FIG. 1;

FIG. 4 is a right side view of the football hooded bath garment of FIG. 1; the left side view of the football hooded bath garment is symmetrical to the view shown in FIG. 4; and,

FIG. 5 is a top plan view of the football hooded bath garment of FIG. 1.

The bottom view of the football hooded bath garment is plain and unornamented and, thus, is not illustrated in the accompanying drawings.

The broken line showing of the figure and indicia is for illustrative purposes only and forms no part of the claimed design.
